Primary Examiner — John A Voytek

(74) Attorney, Agent, or Firm — Morse, Barnes-Brown & Pendleton, P.C.; Sean D. Detweiler, Esq.

(57) **CLAIM**

The ornamental design for an aircraft moon roof, as shown and described.

DESCRIPTION

FIG. 1 is a left side plan view of the aircraft moon roof; and, FIG. 2 is a front right isometric elevated view of the aircraft moon roof.

The broken line showing of the aircraft is for the purpose of illustrating the environmental structure in which the claimed elements are found and forms no part of the claimed design.

1 Claim, 2 Drawing Sheets*Fig. 1*
